CLAIM

The ornamental design for an electric steam iron, as shown and described.

DESCRIPTION

FIG. 1 is a front, top and left side perspective view of an electric steam iron showing our new design;

FIG. 2 is a left side elevational view thereof;

FIG. 3 is a right side elevational view thereof;

FIG. 4 is a top plan view thereof;

FIG. 5 is a front elevational view thereof; and,

FIG. 6 is a rear elevational view thereof.

The broken lines showing of the electrical cord is for illustrative purposes only and forms no part of the claimed design.
